UNITED STATES PATENT OFFICE.

HERBERT ROBINSON, OF HALIFAX, ENGLAND, ASSIGNOR TO JOSEPH WILD & CO., OF NEW YORK, N. Y.

DESIGN FOR A CARPET-PATTERN.

Specification forming part of Design No. 5,803, dated April 16, 1872.

Specification describing a new and original Design for a Carpet, invented by HERBERT ROBINSON, of Halifax, in the county of York, England.

The accompanying photograph fully illustrates my new design.

This invention relates to two new designs for a carpet—one on the border and the other on the body of the carpet.

The border is made with an outer row of pointed figures, next to which there is a row of small squares, succeeded by an undulating line carrying floral tufts, as shown. The ground-

work of the carpet is composed of a succession of figures, all of the same design, and all lozenge-shaped, with zigzag outline and internal ornamentations, as shown.

I claim as my invention—

1. The design for the border of a carpet, as shown.
2. The design for the groundwork of a carpet, as shown.

H. ROBINSON.
